UNITED STATES PATENT OFFICE

CHARLES WESLEY JONES, OF GLEN RIDGE, NEW JERSEY, ASSIGNOR TO SONS-CUNNINGHAM REED & RATTAN CO., INC., OF NEW YORK, N. Y., A CORPORATION OF NEW YORK

DESIGN FOR A FRAME OF A CHAIR OR SETTEE

Application filed June 25, 1930. Serial No. 36,171. Term of patent 7 years.

To all whom it may concern:

Be it known that I, CHARLES WESLEY JONES, a citizen of the United States, residing at Glen Ridge, in the county of Essex and State of New Jersey, have invented a new, original, and ornamental Design for the Frame of a Chair or Settee, of which the following is a specification, reference being had to the accompanying drawing, forming part thereof.

The drawing shows in perspective a chair frame embodying my new design, it being understood that the design, shown in full lines, is repeated, as indicated by dotted lines, at the other end of the chair, or, as it may be, at the other end of the settee.

I claim:

The ornamental design for a frame of a chair or settee, as shown and described.

In witness whereof, I have hereunto set my hand.

CHARLES WESLEY JONES.
